PERCUSSION DETONATING COMPOSITION

André Blanc, Salaise-sur-Sanne, France

No Drawing. Application November 6, 1931,
Serial No. 573,524. In France November 7,
1930

1 Claim. (Cl. 52—23)

The invention relates to a safe detonating play-
thing designed to be employed several times,
while the playthings made up with the so-called
"detonating peas" can only be employed once, be-
cause the whole detonating substance burns at
once.

It is also known that, repeated detonations can
be obtained by throwing two spherical bodies
against each other, of which one has been coated
with potassium chlorate and the other with red
phosphorus.

The present invention is based upon the use of
phosphorus sesquisulphide (P_4S_3) as detonator,
with an oxidizing substance such as potassium
chlorate, in a composition which is coated over
the same spherical body.

By throwing such a spherical body against a
hard surface, a detonation is obtained. Instead
of phosphorus sesquisulphide, one may use red
phosphorus, but the detonation is essentially
weaker.

An example of the composition of coating for
a spherical body according to my invention is
as follows:

	Grains
Phosphorus sesquisulphide	30
Arabic gum	115
Magnesium carbonate	20
Calcium carbonate	5
30 Potassium chlorate	80
Iron sesqui oxide (red ochre)	40

This mixture is moistened with just enough
water to obtain a paste, which is coated on a
hard body, such as a stone for example. It is
advisable to protect the coated stone with a jacket
such as paper, paste board, plaster and the like.
Such a stone is ready for use and can be thrown
repeatedly a number of times against a hard
surface to produce repeated detonations.

From the foregoing it will be understood that
the present invention is based upon the well
known combustible properties of phosphorus ses-
quisulphide (P_4S_3) under the action of an oxidizing
substance, such as potassium chlorate in the
presence of an adhesive substance (arabic gum)
a composition to which neutralizing and retard-
ing bodies are added in predetermined propor-
tions:

50	Magnesium carbonate (CO_3Mg)
	Calcium carbonate (CO_3Ca)
	Red ochre (Fe_2O_3)

substances which under suitable proportions give
to the above mentioned composition such a sta-
bility that the combustion of the phosphorus ses-

quisulfide under the action of the potassium chlo-
rate takes place only at the point of contact when
the coated body is thrown against a hard sur-
face. And this may be done more than forty
times as the paste formed by the composition 60
firmly adheres to the pebble or other hard body.
Therefore I not only substitute phosphorus ses-
quisulfide for yellow phosphorus heretofore em-
ployed, but also add neutralizing bodies to the
composition heretofore known, throwing the ob-
jects prepared in this manner violently against
a hard and dry surface, as many detonations are
obtained as the throwing is repeated (more than
forty times).

This mixture may be employed on a flat object 70
or in serpentine rolled paper or pasteboard,
where it is laid in the form of globules.

Among various playthings which are manufac-
tured with the above described detonating mix-
ture, are exploding pebbles, or "detonating peas" 75
made out of a hard core (stone, metal or artifi-
cial body) and then coated with said paste, and
afterward covered with a protecting paper.

It is a main point of the process that the coat-
ing be as uniform as possible on the whole sur- 80
face of the pebble or other body, to get after dry-
ing, a great number of successive detonations,
as is desired.

Such uniform coating is obtained as follows:

The mixture made of phosphorus sesquisul- 85
fide, gum arabic, magnesium carbonate, potas-
sium chlorate, ochre and calcium carbonate,
moistened with water, is poured into a clean bar-
rel. Pebbles are added, about a thousand in num-
ber, and the barrel is closed and rotated by a 90
handle crank till the surface of the pebbles is
uniformly and regularly coated with the paste.

The pebbles are then poured out of the barrel,
and wrapped in small paper jackets, to prevent
them from sticking together. They are then 95
spread on grating hurdles and dried.

What I claim as my invention and desire to
secure by Letters Patent of the United States is:

A percussion detonating composition consist-
ing of phosphorus sesquisulfide 30 grams, gum 100
arabic 115 grams, magnesium carbonate 20 grams,
calcium carbonate 5 grams, potassium chlorate
80 grams, iron sesquioxide (red ochre) 40 grams.

ANDRÉ BLANC.
